UNITED STATES PATENT OFFICE.

ROBERT ZAHN, OF PLAUE, GERMANY; ALFRED RIETZSCH ADMINISTRATOR OF SAID
ZAHN, DECEASED.

EMBROIDERING-MACHINE.

1,105,233.

Specification of Letters Patent. Patented July 28, 1914.

Application filed January 23, 1913. Serial No. 743,845.

To all whom it may concern:

Be it known that I, ROBERT ZAHN, a subject of the German Emperor, residing at Plauen, in Vogtland, in the Kingdom of 5 Saxony, Germany, have invented certain new and useful Improvements in Embroidering-Machines, of which the following is a specification.

To produce high relief, as, for instance, a 10 button-shaped part, or embroidery work, two methods have been hitherto used. One consists in that the part which is to be the high relief is produced by a great number of intersecting and overlapping stitches 15 whereby a sort of padding is obtained, which is then covered by smooth and parallel flat stitches. The other method which is less tedious than the former, consists in that a soft inlay or filling of the desired 20 shape, area and thickness is placed at the point where the relief is desired, then this filling first by a few stitches is fastened to the fabric and finally its entire surface is covered by a great number of smooth and 25 parallel flat stitches. The first named method is disadvantageous for machine embroidery and particularly for such produced by automatic machines, because in view of the considerably high expense incurred by 30 the installation of such automatic machines, the loss of time necessary to make the innumerable stitches renders the work not economical and this so much more since the consumption of great quantities of thread 35 requires a frequent exchange of the shuttles, during which periods the machine must be at rest. The second method referred to is comparatively simpler and requires less thread. The insertion of the inlay or filling 40 hitherto has been done by hand. With machines that are equipped with about a thousand needles, the attendants would have to apply by hand a filling to each needle, and during this work the machine would have to 45 be at rest. It is therefore obvious that even the second method would be inefficient for machines of the sizes now generally used.

It is the object of this invention to provide means whereby the second method may 50 be efficiently utilized for machine embroidery.

My invention will be more easily understood by reference to the accompanying

drawing, which more or less diagrammatically illustrates the construction and operation of my new device. 55

In the drawing, in which similar reference characters denote corresponding parts, so much of the embroidering machine is shown as is necessary to fully understand 60 the operation of my new device, Figure 1 showing a side view of the automatic embroidery machine equipped with my new device; Fig. 2 a plan view of the device; Figs. 3 and 3^a similar views as Fig. 1 of a 65 modified construction of the device in two different positions and Fig. 4 a partial plan view of the modified device.

In the drawing let X—X denote the embroidery surface or the fabric. 70

7 and 7 are the upper and lower rows of needles fixed to the needle bars 7' which are operated in well known manner by suitable means (not shown). Arranged above and crosswise to the needles (see Fig. 2) is a 75 spindle 8 which is suitably supported in bearings 8', and to the ends of which are fixed bell crank levers 3, 3' of which the arms 3 are somewhat curved in the manner shown in Fig. 1. The free ends of the arms 80 3 are connected by a bar or rail 2 extending parallel to the shaft or spindle 8 and which carries a series of receptacles 1 adapted to hold the inlay or filling pieces 1' which may be flat, ring shaped or otherwise, just as required. There is one receptacle for each needle. The other arms 3' of the bell crank levers for the upper and lower needle rows of the embroidering machine are connected by links or rods 4 and through the medium 85 of a rod 5 are operated from the jacquard mechanism which is indicated in the drawing by 6. The jacquard mechanism, according to the jacquard card (not shown), and in well known manner, causes the arms 3 90 through the medium of the rod 5 and link 4 to swing from the dotted line position to the full line position and back (Fig. 1) so that the receptacles will describe circular paths and during their downward movement will be brought into the range of the 95 stitching needles 7.

The receptacles 1 are formed with a slanting bottom 1'', which terminates into a narrow downwardly projecting chamber 1², 105 which is open at its bottom at 1³ and having

in its center recesses 1⁴. When the levers 3, swing downwardly and the receptacles 1 are brought into the range of the needles 7, the lowermost of the inlay pieces, which are stored on top of one another in each receptacle and rest on the slanting bottom 1', slides into the slot or chamber 1² so as to lie opposite the needle 7 and to be stitched by it to the fabric. Thus the inlay pieces, one by one, as the receptacles are swung downwardly, are fixed to the fabric and covered by flat stitches by the needles, which in well known manner and through the medium of the jacquard mechanism are caused to perform their different functions. But instead of having the receptacles swing together with the levers, the same may be fixed and there may be means to receive and convey the filling pieces from the receptacle into the range of the needles. Such construction is shown in Figs. 3, 3^a and 4. Here the chute like receptacles 1^a, are carried by a common stationary rail or bar 12, and their open slanting bottoms are closed by slides 14, guided on rods or pins 15. The transversal bars 2' connecting the levers 3, carry grippers 13, which are adapted, when swung from the position shown in Fig. 3 to the position shown in Fig. 3^a, to shift the slides 14 upwardly and to thereby open the bottom of the receptacles 1^a. The inlay or filling pieces 1', which are stored in these receptacles on top of one another and normally rest on the slides 14, will then be permitted to slip out one by one onto the said grippers 13, which will be carried with the levers 3 downwardly into the range of the needles 7. Each of the grippers may be in the shape of a narrow, pan-shaped receptacle, which at one end is provided with a flange 13' adapted, when coming into contact with the slide 14, to shift the latter upwardly. In the center the said grippers are recessed as at 13², to allow the needles to stitch through the inlay pieces, held by the grippers. As the chamber 1² in the construction according to Fig. 1 or the parts 13 are open at the end which when swung downwardly would be down, means must be provided to hold the inlay pieces 1' from falling out.

According to the construction, Figs. 3-4, the inner surface of the part 13 is provided with prongs or tooth-shaped projections 16 which will grip the filling piece during the downward stroke of the parts 13 and release it when the parts 13 begin their upward or return stroke.

Any known means suitable for the purpose of holding the inlay piece in position in chamber or part 13 may be made use of and the same may vary according to the material used. I therefore do not wish to restrict myself to any particular construction of such means.

Since the manner of conveying the inlay

pieces from the storage receptacle into the range of the needles, may also be varied without departing from the spirit of my invention, I do not wish to confine myself to the details herein shown and described.

What I claim and desire to secure by Letters Patent is:

1. In a jacquard embroidering machine, the combination with embroidering needles, of an inlay or filling feeding device, comprising storage receptacles for containing inlay or filling pieces and jacquard controlled means for conveying the said inlay pieces into the range of the embroidering needles.

2. In a jacquard embroidering machine, the combination with embroidering needles, of an inlay or filling feeding device, comprising stationary storage receptacles for containing inlay or filling pieces and jacquard controlled means for conveying the inlay pieces from said receptacles into the range of the embroidering needles.

3. In a jacquard embroidering machine, the combination with the embroidering needles, of an inlay or filling feeding device, comprising storage receptacles for containing inlay or filling pieces and jacquard controlled rocking members for bringing the inlay pieces into the range of the embroidering needles.

4. In a jacquard embroidering machine, the combination with embroidering needles, of an inlay or filling feeding device, comprising stationary storage receptacles for containing inlay or filling pieces, there being one receptacle for each embroidering needle, and each having an open bottom, means for normally closing said open bottom and jacquard controlled means for operating said closing means and for conveying the inlay or filling pieces from said receptacles into the range of the said embroidering needles.

5. In a jacquard embroidering machine, the combination with embroidering needles, of an inlay or filling feeding device, comprising stationary storage receptacles for containing inlay or filling pieces, there being one receptacle for each embroidering needle and each having an open bottom, means for normally closing said open bottom and jacquard controlled rocking members for conveying the inlay or filling pieces from said receptacles into the range of the said embroidering needles.

6. In a jacquard embroidering machine, the combination with embroidering needles, of an inlay or filling feeding device, comprising stationary storage receptacles for containing inlay or filling pieces, there being one receptacle for each needle and each receptacle having an open bottom, means for closing said open bottom and jacquard controlled means for operating said closing means and having a member to receive the

inlay pieces from said receptacle and to convey the same into the range of the embroidering needles.

7. In a jacquard embroidering machine, 5 the combination with embroidering needles, of an inlay or filling feeding device, comprising stationary storage receptacles for containing inlay or filling pieces and jacquard controlled rocking members, one for 10 each receptacle and each rocking member having means to receive and convey a filling piece from the corresponding receptacle into the range of the embroidering needles.

8. In a jacquard embroidering machine, 15 the combination with embroidering needles, of an inlay or filling feeding device, comprising stationary storage receptacles for

containing inlay or filling pieces, there being a receptacle for each needle and each receptacle having an open bottom, a sliding member 20 for the open bottom of each receptacle, jacquard controlled rocking members, one for each receptacle, and a gripping member on each rocking member adapted to operate the sliding member of the corresponding 25 receptacle and to receive and convey an inlay or filling piece from said receptacle into the range of the embroidering needles.

In testimony whereof I affix my signature in presence of two witnesses.

ROBERT ZAHN.
